UNITED STATES PATENT OFFICE.

JOSEPH VOLMER, OF DECATUR, INDIANA, ASSIGNOR, BY DIRECT AND MESNE ASSIGNMENTS, OF ONE-HALF TO HERBERT B. FRANCE AND ONE-HALF TO CLAY ENGLE, BOTH OF DECATUR, INDIANA.

CUFF-FASTENER.

1,059,790.

Specification of Letters Patent.

Patented Apr. 22, 1913.

Application filed February 21, 1912. Serial No. 679,154.

To all whom it may concern:

Be it known that I, JOSEPH VOLMER, a citizen of the United States, residing at Decatur, in the county of Adams and State of Indiana, have invented certain new and useful Improvements in Cuff-Fasteners; and I do declare the following to be a full, clear, and exact description of the invention, such as will enable others skilled in the art to 10 which it appertains to make and use the same.

This invention relates to improvements in cuff fasteners and more particularly to those made of a single piece of metal and yielding throughout its entire structure.

One object of the invention is therefore in the provision of a simple, practical and efficient device of the character described whereby the construction of the same is of 20 such a nature that the usual button holes of the cuff of a garment are dispensed with.

Another object of the invention resides in the particular formation of the device whereby the inner and outer surfaces of the 25 cuff adjacent to the edges thereof are properly shaped, connected and held in proper alinement, the outer enlarged rounded edges of said cuff being snugly received and yieldingly engaged, whereby the fastener can be 30 conveniently adjusted along the edges of the cuff without removal therefrom.

Further and important features of the invention reside in the particular construction and relative formation of the fastener, 35 as hereinafter described and claimed, whereby the results referred to are successfully carried out.

In the drawings:—Figure 1 is a perspective of the complete invention; Fig. 2 is a 40 longitudinal section of the invention as applied to a cuff; Fig. 3 is a side elevation of the fastener applied.

The fastener is composed of a single piece of flat metal having a yielding convex body 45 2 from which correspondingly shaped flat converging walls 4 extend forming the loop 3 and the inner yielding member of the cuff clamping jaws of the fastener. The opposite outer yielding jaws 7 are formed at a 50 slight angle to the jaws 4, to form the cuff receiving loops 6, and the ends of said jaw are projected beyond the rounded portion 2 for a purpose hereinafter described. As

clearly shown the outer surfaces of the jaws 7 are provided with a plurality of adjacent 55 depressions 8 forming corresponding projections on the inner faces of said jaws, the latter being located near the opposite straight edges of the said jaws 7 and adapted to engage with the outer surfaces of the 60 cuff adjacent to the edges thereof to be connected and formed.

An important feature of the invention is in the particular formation of the fastener which yieldingly connects the inner and 65 outer jaws 4 and 7 respectively the same being enlarged and rounded as shown at 9 whereby the fastener is rendered sufficiently yielding and the edges of the cuff 70 snugly confined therein permitting the fastener to be adjustable along the edges of the cuff without removing the fastener therefrom.

It will thus be seen that by extending the ends of the outer jaws 7 beyond the centrally disposed convex portion 2, and by flaring the said jaws from the inner converging members 4, the edges of the cuff can be readily inserted between the yielding clamping jaws and when the fastener is 80 properly positioned and attached to the cuff the same cannot be accidentally released. It will further be noted that by the construction of the fastener the edges of the cuff are yieldingly connected and will compensate for any irregularities of the same when 85 in use therefore assisting in preserving the original and desirable formation of the cuff when applied. Further it will be noted that a handkerchief, glove or other similar article can be readily inserted between and temporarily held by the rounded connected ends 9 of the fastener, which feature of the invention will be greatly appreciated.

What I claim is:—

A cuff fastener comprising a flat strip of 95 spring metal bent at two portions of its length to provide a plurality of loops, each of the loops having extended therefrom an inclined jaw, said jaws connected together 100 at their terminals opposite the loops with a concavo-convex yielding portion, the other ends of the loops having also extending therefrom inclined yielding jaws in substantial parallelism with the first jaws, said 105 second named jaws having a longitudinal

smooth surface provided on opposite sides with inwardly disposed depressions which are adapted to be embedded into the upper surface of the cuff, and the marginal portions of the cuff being adapted to be inclosed within said loops.

In testimony whereof I have hereunto

set my hand in presence of two subscribing witnesses.

JOSEPH VOLMER
